DESIGN FOR A RESTAURANT BUILDING OR SIMILAR ARTICLE

Otis Ferrill, Whittier, Calif.

Application July 6, 1948, Serial No. 147,390

Term of patent 3½ years

(Cl. D13—1)

To all whom it may concern:

Be it known that I, Otis Ferrill, a citizen of the United States, residing in the city of Whittier, in the county of Los Angeles and State of California, have invented a new, original, and ornamental Design for a Restaurant Building or Similar Article, of which the following is a specification, reference being had to the accompanying drawing, forming a part thereof.

I claim:

The ornamental design for a restaurant building or similar article, as shown.

OTIS FERRILL.
